John W. Gheen

Inventor

UNITED STATES PATENT OFFICE.

JOHN W. GHEEN, OF LOS ANGELES, CALIFORNIA.

PRESSURE REGULATOR.

Application filed February 24, 1920. Serial No. 361,013.

To all whom it may concern:

Be it known that I, JOHN W. GHEEN, a citizen of the United States, residing at Los Angeles, in the county of Los Angeles, State 5 of California, have invented a new and useful Improvement in Pressure Regulators, of which the following is a specification.

My invention relates to an improvement in pressure regulators having a flexible dia- 10 phragm by which a valve is operated, and my object is to provide a means whereby an extremely sensitive instrument may be produced.

In this type of pressure regulators the 15 disc covering the diaphragm is guided in its movement either a shaft in the center or a piston forming the disc. In this case the guides must be long to prevent cramping, making the pressure regulator cumbersome 20 and otherwise impracticable. Where the disc has a shaft in the center for a guide, the least inaccuracy, either in the stem or the disc being out of center or the diaphragm having more stretch to one side of the center or a looseness 25 in guides destroys the sensitiveness of the regulator. With my invention the pressure is taken from the disc from three or more points near the edge, and by means of pivoted levers converging at a point directly 30 over the center of the disc, so that the pressures are always toward and never away from the center. This principle of suspen- 35 sion from a number of points and converging to a central point, is employed in platform scales, and for the first time is by me used in pressure regulators.

I have illustrated my invention in its most simple form in the accompanying drawings, in which—

Fig. 1 is a top plan view of a pressure regulator embodying the principles of my invention, the view being taken looking downward in Fig. 2.

Fig. 2 is a vertical sectional detail on the line 2—2 of Fig. 1 and looking in the direction of the arrows.

The base plate A is circular in plan and has a semispherical depression a at its center, a finished flat face b around the depression a; a bearing 1, extending outwardly at one side and a supporting ledge 11, extending outwardly at the side diametrically opposite the bearing 1.

The thin flexible diaphragm B fits upon 55 the flat face C and covers the depression A.

The clamping plate 3 fits upon the dia- 60 phragm B around the depression a and is held in place by cap screws 2 to make a closed chamber D between the base plate A and the diaphragm B. The pressure pipe 20 has an arm connected into the opening 21, leading through the center of the base plate A to the chamber D. The valve casing 16 is supported by the ledge 11. The valve stem 14 connects 17 and is connected to the 65 valve 15 in the valve casing 16. An arm E connects the pressure pipe 20 to one side of the valve casing 16 and the outlet 22 leads from the other side.

A bifurcated post 10 extends upward from 70 the clamping plate 3 in line with the bearing 1 and the ledge 11. The lever 9 is pivoted in the bifurcation at the upper end of the post 10 and the short end of the lever 9 rests upon the upper end of the stem 14. The 75 pressure in the pipe 20 and arm E tends to hold the valve 15 closed. A retractile coil spring 12 connects the long end of the lever 9 to the bearing 1, arm 9, the tension of the 80 spring 12 being exerted to swing the short end of the lever 9 upward and allow the valve 15 to close.

The details of the three point equalizer connection between the pressure plate 18 and the lever 9 are as follows:

Bifurcated bearing posts 5, 5^a and 5^b, extend upward from the clamping plate 3 and are arranged concentric and radially relative to the chamber D. Balls 19, 19^a and 19^b, are mounted upon the pressure plate 18. 90 Levers 4, 4^a and 4^b are pivotally connected to the posts 5, 5^a and 5^b, and rest upon the balls 19, 19^a and 19^b. Balls 6, 6^a and 6^b are mounted upon the inner ends of the levers 4, 4^a and 4^b. An evener plate 7 is mounted upon the balls 6, 6^a and 6^b. A ball 8 is mounted upon the center of the evener plate 7 and the lever 9 rests upon the ball 8. The pressure in the chamber D against the dia- 95 phragm B raises the plate 18 against the equalizer connection and raises the long end of the lever 9 against the tension of the spring 12. The tension of the spring 12 may be adjusted by manipulating the nut 13. When the pressure in the pipe 20 ceases, the 100 diaphragm B will fall down upon the bottom of the chamber D and the spring 12 will hold the parts under sufficient tension 105 to keep them in working order. The equalizer connection prevents the pressure plate 110

18 from rocking upon the diaphragm, so that the pressure plate will move with the least friction.

I claim:

5 1. In a pressure regulator, a base plate having a depression, a diaphragm covering the depression, a clamping plate against the diaphragm around the depression and secured to the base plate, posts extending upwardly from the clamping plate and arranged concentric to the depression, a pressure plate upon the diaphragm, balls upon the pressure plate near its edge, levers connected to the posts and bearing upon the 10 balls, second balls upon the inner ends of

the levers, an evener plate upon the second balls, a ball upon the center of the evener plate, a lever pivotally mounted and engaging the ball, a spring pulling the lever against the ball, and a valve connected to the 20 opposite end of the lever from the spring.

2. In a pressure regulator, a base plate, a diaphragm mounted upon the base plate and forming a pressure chamber, a pressure plate upon the diaphragm, a valve, a lever connected to the valve and extending over the pressure plate, and a three point equalizer connection between the pressure plate and the lever. 25

JOHN W. GHEEN.
